UNITED STATES PATENT OFFICE.

ARTHUR H. PENFIELD, OF NEW YORK, N. Y.

APPARATUS FOR CONCENTRATING ORE.

Application filed August 11, 1922. Serial No. 581,157.

To all whom it may concern:

Be it known that I, ARTHUR H. PENFIELD, citizen of the United States, residing at New York, in the county of Queens and State of New York, have invented certain new and useful Improvements in Apparatus for Concentrating Ore; of which the following is a specification.

The invention relates to improvements in an apparatus for concentrating ores. It has been proposed in the prior art to separate ore from gangue by passing the ore and gangue suspended in water through a series of containers where a partial separation has been effected, but these prior art attempts have not been highly successful due to the formation of eddies in the water travel which causes gangue to become mixed with the concentrate.

It is an object of this invention to provide a means for concentrating ores wherein a sharp and clear separation of the metallic substances from the gangue is effected. With this conception in mind the invention more specifically contemplates an apparatus wherein no opportunity for the formation of eddies in the flowing water is presented, thereby resulting in a clean and effective separation of the ore from the gangue.

In carrying out my invention I preferably employ an apparatus consisting of a series of communicating vertically disposed compartments in the lower one of which I admit water and comminuted ore and gangue and continue to admit such materials until the water rises and fills all of the receptacles and flows out through a discharge pipe. When the receptacles are filled and a concentration of ore has resulted, I then close the valves of the two upper receptacles leaving the water and ore in each compartment quiescent for a period thereafter and opening the valve in the lower compartments to discharge the concentrate therein. The valves of the two upper receptacles are then opened to discharge the concentrate after which the compartments are flushed with a stream of water. It will be understood that the compartments are all provided with smooth round surfaces to prevent the formation of eddies, and that likewise each receptacle is provided with a controlling valve.

In the accompanying drawings I have

shown a preferred embodiment of this invention.

In the drawings, Figure 1 represents a vertical sectional view of the apparatus showing valves opened; and Figure 2 is a similar view to Figure 1 showing valves closed.

Referring now more particularly to the drawings, wherein like reference characters indicate corresponding parts, the numeral 1 designates a base or support which may be of any convenient form. Positioned on this support or base are a plurality of ore compartments 2, 3 and 4 communicating through conduits 5 and 5' which conduits receive valves 6 and 6'. The lower compartment 4 is also provided with a discharge 7 controlled by a manually operable valve 8. As is clearly disclosed in the drawings the walls of the compartments 2, 3 and 4 are all formed so as to present smooth and continuous surfaces for reasons which will hereinafter appear and likewise these compartments are of progressively increasing capacities.

Positioned adjacent the compartment 4 is a hopper 9 mounted upon a support 10 and communicating with the upper portion of this compartment through a pipe 11 receiving a screw feed conveyor 12 operated by the pulley 13. Pulverized ore and contained gangue are introduced to the hopper 11 and fed by the conveyor 12 directly into the lower compartment 4. Into this compartment 4 I also introduce a water feed pipe 14, which extends downwardly through the compartment to a lower end communicating with a water feed pipe 15 controlled by the valve 16. Water is thus introduced to the lower part of the compartment 4 when the valve 8 has been closed and ore likewise enters said compartment through the feed 11.

A water feed pipe 17 communicates with the feed 15 and enters the upper compartment through the valve controlled handle 18. Ordinarily, this valve is closed and is usually only opened when a cleaning of the compartment is desired. The upper compartment 2 communicates with the water outlet pipe 19 leading therefrom and controlled by the valve 20. This pipe is an exit for any suspended gangue contained in the rising water that has passed through the compartments 2, 3 and 4.

2
In carrying out my invention ore is introduced together with water to the compartment 4. The valve 8 is closed and the valves 6 and 6' opened. The flow of water continues with the introduction of the ore until the compartments 2, 3 and 4 have been filled with concentrate, it being understood that during this upflowing action of the water no eddies or local currents are formed and that the continuously flowing water which travels at a substantially uniform velocity through the compartments carrying in suspension therein the fine particles of gangue which are discharged through the outlet 19. By arranging the walls of the compartments in the manner disclosed local eddies or disturbances of the water are prevented and in this way the gangue is not caused to mix or become associated with the settling concentrate which begins to settle as soon as it is introduced to the different compartments. The velocity of the water is of course so regulated that the concentrate will settle while the lighter gangue flows out through the outlet pipe 19.

After the compartments have been substantially filled with concentrate the flow of water and the ore through the feeds 11 and 15 respectively is discontinued and the valves 6 and 6' closed. The ore in the different compartments 2, 3 and 4 is then permitted to settle which occurs in a short period of time because of the stagnant condition of the water and when this concentrate has settled the valve 8 of the lower compartment is opened and the contents of this compartment discharged into a suitable receiver through the pipe 8. When the contents of this compartment have been discharged then the valves 6 and 6' are opened and the concentrate in the compartments 2 and 3 together with the water discharges through the compartment 4 and out through the outlet 5. The valve 18 is then opened in the water feed pipe 17 and the compartments then flooded or cleansed by a supply of water flowing therethrough. The valve 8 is then closed and the valves 6 and 6' opened and a new supply of water introduced to the compartment 4 wherein the operation above described is repeated.

Having thus described my invention, what I claim is:

55 1. An ore concentrating apparatus having a plurality of suspension compartments, communications between said compartments, means for introducing ore and water to the lower compartment to pass through said communicating compartments wherein the ore settles, means for discharging water and gangue from one of the compartments, valves in said communications between said compartments, and means for operating said valves.

2. An ore concentrating apparatus having a plurality of suspension compartments, communications between said compartments, means for introducing ore and water to the lower compartment to pass through said communicating compartments wherein the ore settles, means for discharging water and gangue from one of the compartments, valves in said communications between said compartments, means for operating said valves, and a flushing pipe for conducting water to the upper compartments and a valve controlling said pipe.

3. An ore concentrating apparatus comprising a plurality of suspension compartments having smooth continuous inner surfaces, communications between said compartments, means for introducing ore and water to the lower compartment to pass through said communicating compartments wherein no eddies are formed and the ore settles, means for discharging water and gangue from one of said compartments, valves in said communications between said compartments, and means for operating the valve.

4. In an ore concentrating apparatus, the combination with a plurality of communicating compartments, means for introducing ore in water suspension to one of said compartments to pass successively through the communicating compartments where ore settles, means for discharging water with suspended gangue from one of the compartments, and means for discharging the settled ore separated from its gangue from said compartments.

5. In an ore concentrating apparatus, the combination with a plurality of communicating compartments, means for introducing ore in water suspension to one of said compartments to pass successively through the communicating compartments where ore settles, manually operable valves between said compartments, means for discharging water with suspended gangue from one of the compartments, means for discharging the settled ore separated from its gangue from said compartments, and means for flushing each compartment including manually operable valves, one valve being provided for each compartment whereby the contents of the compartments may be independently discharged after the discharge of ore therefrom.

6. An ore concentrating apparatus, comprising a plurality of vertical compartments, each having smooth inner surfaces, communications between said compartments, means for feeding ore in water suspension to the lower compartment to pass successively through said compartments and into which compartments the ore settles, valves between said compartments, means for discharging the water with suspended gangue from the

upper compartment, and means for discharging the separated ore accumulating in each of said compartments.

7. An ore concentrating apparatus, comprising a plurality of vertical compartments, each having smooth inner surfaces, communications between said compartments, means for feeding ore in water suspension to the lower compartment to pass successively through said compartments and into which compartments the ore settles, means for discharging the water with suspended gangue from the upper compartment, means for discharging the separated ore accumulating in each of said compartments, said means including a discharge from the lower compartment, and valves in the communications between the successive compartments, said valves being adapted to be closed when water and ore are no longer admitted to the lower compartment to permit the ores there-

in to rapidly settle, and means for independently operating the valves so that they may be opened successively.

8. In an ore concentrating apparatus, the combination with a plurality of vertically disposed compartments of progressively decreasing sizes, each of said compartments having smooth inner surfaces, means for establishing communication between said compartments, valves in said communications, means for feeding ore in water suspension to the lower compartment to pass successively through said communicating compartments where the ore settles, means for discharging gangue in water suspension from one of said compartments, and means for discharging the separated or accumulating in said compartments.

In testimony whereof I affix my signature.

ARTHUR H. PENFIELD.
